GAS ENGINE

Friedrich Hagenmüller, Nuremberg, Germany, assignor to Maschinenfabrik Augsburg-Nürnberg A. G., Nuremberg, Germany

Application September 28, 1939, Serial No. 297,002
In Germany October 6, 1938

6 Claims. (Cl. 123—173)

The present invention relates to engines and more particularly pertains to the stay bolts arrangements for double cylinder engines.

In the known large, double-acting gas engines with two cylinders disposed one behind the other in the same axis as the engine frame, the two cylinders, the intermediate piece which connects the two cylinders with one another and the rear guide are connected with one another by means of stud-bolts which are usually fixed in the ends of the cylinders. This involves the disadvantage that the cooling spaces of the cylinders become difficult of access and when one of such longitudinal stays is to be replaced it is necessary to dismount the cylinder for changing the stay. Danger to the connecting flanges and at their fillets is also not excluded. Other disadvantages of this construction are to be found in the great expenditure of material and the costly machining, also in the difficulties presented when assembling and dismantling such an engine.

All these disadvantages are overcome by the present invention wherein the entire engine from the front frame to the rear guide is held together exclusively by longitudinal tension-stressed stay bolts, all tensional stresses in the parts clamped between the stay bolts being avoided. These parts are only stressed in compression. Numerous such stays may be employed or only two stay bolts may be provided, one on the right-hand side and one on the left-hand side of the engine.

As the cylinders and the adjacent parts heat up during operation and thereby become longer, the stay-bolts are subjected to additional stresses. These are avoided or reduced either by taking the water flowing out of the cooling spaces through a longitudinal bore of these stay-bolts or by surrounding the stay-bolts with a sheet metal sheath and causing the outflowing warm cooling water to flow through the space between the sheaths and the stay-bolts.

When there are only two stay-bolts and in order to keep the stressing of the same equal on both sides of the machine and to prevent any change occurring through one-sided heating, provision may be made, that the stay-bolts will be equally heated by the exhaust pipe and the hot air rising from it. This is effected by mounting the exhaust pipe vertically below the longitudinal axis of the engine.

The two cylinders may be brought directly against one another in such a manner that between them there is disposed only a common cylinder cover which is clamped between the two

cylinder walls. Preferably only the flange of this cylinder cover will be clamped between the ends of the cylinders, as in this way the overall length will be shortest. For holding the single stuffing box in this cylinder cover the arrangement will with advantage be such that the body of the cylinder cover is divided into two equal halves, so that each half of the stuffing box is disposed in one of these two cover halves. A further feature of the invention is to provide this middle stuffing box with a temperature measuring device, for immediately indicating abnormal heating due to any leakage or lack of oil or the like occurs.

Other and further features and objects of the invention will be apparent from a consideration of the accompanying drawings and the following detailed description wherein several exemplary embodiments of the invention are disclosed.

In the drawings:

Fig. 1 is a side elevational view of an engine embodying the invention.

Fig. 2 is a rear end view of the engine.

Fig. 3 is an elevational view of modified means for controlling the temperature of the stay bolts.

Fig. 4 is an end elevational view of the engine shown in Fig. 3.

Fig. 5 is a sectional view of means for covering the adjacent ends of the cylinders.

Fig. 6 is a sectional view of a modified cylinder head.

Referring to the drawings there is shown in Fig. 1 an engine frame 1 which is provided with bearings for the crankshafts. The engine includes a forward cylinder 2, an intermediate cylinder head 3, a rear cylinder 4 and a rear guide 5. All the parts 1 to 5 are held together by two longitudinal stay bolts 6 and 7 extending alongside the engine, which with nuts engage at the forward end a lug 8 on the frame 1 and at the rear end a similar lug 9 on the rear guide. Between the cylinders and the other parts there are no connecting screws, stud-bolts or the like.

The warm cooling water coming from the engine is introduced by means of piping 10 into a bore of the longitudinal stay bolts 6 and 7 and flows away through piping 11. The longitudinal stay bolts are thereby brought to about the same mean temperature as that of the engine and consequently additional stresses due to expansions of the engine and of the stay-bolts, caused by differences in temperature, are avoided or at least greatly reduced.

Figs. 3 and 4 show a similar high-power gas engine wherein the longitudinal stay-bolts 12

and 13 are solid and heated by a sheet metal sheath 14 being placed round them and the cooling water coming from the engine being conveyed through the hollow space formed between sheath and the stay-bolts. The supply is by way of the pipe 15 and the discharge by way of the pipe 16.

In this engine the exhaust pipe is disposed vertically below the longitudinal axis of the cylinders. For this purpose the exhaust chambers 17, 18, 19 and 20 are connected with one another by pipes 21, 22 and 23 and through these pipes the exhaust can flow into the pipe 24, from where it passes into the atmosphere. Owing to this position of the exhaust pipe the engine is entirely uniformly heated on both sides by radiation and by the current of air ascending from the exhaust pipe, so that the stresses in the two stay bolts are equal.

Fig. 5 shows the arrangement of the cylinder head between the forward and rear cylinder in an engine, in which there is no other intermediate piece between these cylinders. The cylinder head consists in accordance with the invention of a forward half 25 and a rearward half 26, which are provided at the sides facing one another with flanges 27 and 28 respectively. These flanges are clamped between the end faces 29 and 30 of the two cylinders, the cylinders being connected in the manner already described by longitudinal stay bolts. In this arrangement the stuffing box 31 is disposed in part in one and in part in the other half of the cover and is held between flanges 32 and 33.

For enabling the temperature of the stuffing box 31 to be kept under observation, a thermometer 34 is provided, which extends through a bore 35 into the stuffing box.

A somewhat modified constructional form of the middle cylinder cover is shown in Fig. 6. In this case there is interposed between the halves 34 and 35 of the cover an annular disc 36 which contains the requisite ducts 37 and 38 for cooling oil and so forth. This annular disc extends to the piston rod 39, so that the latter can for instance be directly supplied with oil. The stuffing box is in this case divided by the inner rim of the annular disc 36 into two halves 40 and 41.

What I claim is:

1. In a liquid cooled engine, a crank case frame, a cylinder mounted on the crank case frame, stay bolts holding the cylinder to the

crank case frame, and means guiding the engine cooling liquid adjacent the stay bolts whereby the stay bolts are heated in accordance with the temperature of the cooling liquid.

2. In a liquid cooled engine, a frame, a cylinder mounted on said frame, hollow stay bolts securing the cylinder to the frame, and means guiding the cooling liquid through the hollow stay bolts whereby the temperature thereof varies in accordance with the temperature of the engine cooling liquid.

3. In a liquid cooled engine, a frame, a cylinder, stay bolts holding the cylinder to the frame, a sheath surrounding each stay bolt in a spaced relation, and means for guiding the cooling liquid from the engine through the sheaths whereby the temperature of the stay bolts varies with the temperature of the engine cooling liquid.

4. In a liquid cooled internal combustion engine, a frame, a cylinder mounted on the frame, stay bolts extending along the cylinder holding the cylinder to the frame, means for guiding the cooling liquid from the engine along the stay bolts so that the temperature thereof varies in accordance with the temperature of the engine cooling liquid, and an exhaust pipe disposed vertically below the axis of the cylinder whereby the stay bolts are equally heated with heat released by the exhaust passing through the exhaust pipe.

5. In an engine, two axially aligned cylinders, a divided cylinder head mounted between adjacent ends of said cylinders, a piston rod extending from one cylinder into the other cylinder through an opening in the cylinder head, a flange carried by each part of the divided cylinder head, stay bolts clamping the adjacent ends of said cylinders against said flanges, and said cylinder head having a stuffing box formed in both parts thereof adjacent the piston rod.

6. In an engine, two axially aligned cylinders, a divided cylinder head mounted between adjacent ends of said cylinders, a piston rod extending from one cylinder into the other cylinder through an opening in the cylinder head, a flange carried by each part of the divided cylinder head, stay bolts clamping the adjacent ends of said cylinders against said flanges, said cylinder head having a stuffing box formed in both parts thereof adjacent the piston rod, and a temperature measuring device carried by said cylinder head for determining the temperature of said stuffing box.

FRIEDRICH HAGENMÜLLER.
